POWER-SUPPLY SYSTEM

William Herbert Aldous and Dennis Clark Espley,
Wembley, England, assignors to Hazeline Corporation,
a corporation of Delaware.

Application July 1, 1936, Serial No. 282,470
In Great Britain July 8, 1938

5 Claims. (Cl. 250—27)

This invention relates to a power-translating system and, more particularly, to such a system comprising thermionic rectifiers of the type adapted to provide, from an alternating potential supply, unidirectional operating voltages to a device having terminals adapted for operation at different voltages, the high potential one of its terminals requiring a positive current and the remainder of its terminals requiring a negative current under normal operating conditions. For instance, the rectifier may be utilized to maintain the electrodes of a secondary emission electron multiplier at predetermined mean potentials relative to each other. The characteristic feature of a secondary emission electron multiplier is that it has at least one electrode, for example, a secondary cathode, positive to the most negative electrode, usually the primary cathode or a control grid associated with it, which in operation loses rather than gains electrons and, therefore, needs to be supplied with electrons, that is, a negative current, and has also at least one electrode, for example, another secondary cathode or the output electrode, the mean potential of which in operation is positive to that of the first said electrode. In case such last-mentioned electrode is the anode of an electron multiplier, it is required that electrons must be supplied thereto or, in other words, a positive electron current to such anode is required. Such an electron multiplier effectively acts as a positive resistance with respect to its primary cathode and its anode and behaves as a negative resistance with respect to its primary cathode and its secondary cathodes.

When a discharge device has two or more electrodes which have to be maintained at different mean potentials with respect to a common electrode, it is customary to derive the lower potentials from the higher ones by means of resistances. As this procedure is wasteful in power, it has been proposed to derive the required potentials from separate rectifiers, which yield directly different unidirectional voltages. In order that the saving in power should not be offset by the cost of the additional rectifiers, it has been proposed to make the rectifiers share certain parts in common. The greatest economy would usually be effected by making them share a common cathode, but there are sometimes difficulties in the way of this proposal which will be explained hereinafter.

It is an object of the present invention, therefore, to provide an improved arrangement for

supplying power to a device having a plurality of terminals individually requiring for normal operation different unidirectional operating potentials, the one of the terminals of highest potential requiring positive current thereto, and the remainder of the terminals requiring negative currents.

In accordance with the invention, in a power-translating system including a single load device having a plurality of terminals individually requiring for normal operation different unidirectional operating potentials, the one of the terminals of highest potential comprising an anode electrode requiring a positive current thereto and the remainder of the terminals comprising secondary-cathode electrodes requiring negative current, the values of each of which are dependent upon the values of current to all of the terminals of lesser potential, a power-supply system comprises a rectifier including a cathode and a plurality of anodes. The system includes a plurality of supply circuits for supplying alternating potentials of different values between the several anodes and the cathode, and means for connecting the cathode to the aforesaid one of the terminals and for respectively connecting the anodes of increasingly higher alternating potential to the aforesaid terminals adapted for operation at decreasing unidirectional potentials through their respective supply circuits.

For a better understanding of the invention, together with other and further objects thereof, reference is had to the following description taken in connection with the accompanying drawing and its scope will be pointed out in the appended claims.

Fig. 1 of the drawing is a circuit diagram of a rectifier system utilized to explain the general theory of the invention; while Fig. 2 is a circuit diagram of a power-translating system in accordance with the invention.

In order to bring out the difficulty of supplying unidirectional operating potentials to a conventional multielectrode vacuum tube from a device which is effectively a plurality of rectifiers sharing a common cathode, reference is made to Fig. 1 in which K is a common thermionic cathode co-operating with two anodes A₁ and A₂. These anodes are fed by two transformer windings S₁ and S₂, shown to be entirely independent for clarity, of which the winding S₂ yields a higher, and the winding S₁ a lower, alternating voltage. C₁ and C₂ are filter condensers connected between the cathode K and the other ends of the transformer windings.

In operation, the terminals 2 and 3 are negative with respect to terminal 1, terminal 3 being more negative than terminal 2, as indicated by the voltages in brackets adjacent these terminals.

If now a single load device having two electrodes, positive to a common cathode, is to be supplied from this arrangement, terminal 3 must be connected to such common cathode, terminal 1 to the more positive electrode and terminal 2 to the less positive electrode of such two electrodes. If the electrode connected to terminal 1 is receiving electrons, for example, if it is the anode of a tetrode whose cathode is connected to terminal 3, these electrons can escape by passing from the cathode K to the anode A_h. But if the electrode connected to terminal 2 is also receiving electrons, for example, if it is the screen grid of the tetrode, these electrons cannot escape from anode A₁ to either cathode K or anode A_h. The arrangement is, therefore, not adapted to feed the anode and screen grid of such a tetrode.

On the other hand, if the electrode connected to terminal 3 is the primary cathode of a secondary emission electron multiplier, that connected to terminal 1 is the output electrode, and that connected to terminal 2 is a secondary cathode, the required operating conditions are fulfilled. Under such conditions, the secondary cathode is losing electrons, which can be supplied to it from the cathode K by way of the anode A₁. That fact is the basis of the present invention.

Referring now to Fig. 2, there is shown a power-supply system embodying the invention and including a rectifier 10 comprising a plurality of anodes A₁-A₅, inclusive, all co-operating with a common cathode K and a transformer, including a plurality of supply circuit secondary windings S₁-S₅, inclusive, having a common primary winding P, for applying between each of anodes A₁-A₅, inclusive, and cathode K alternating potentials of progressively increasing values. The rectifying means 10 is used to supply unidirectional operating potentials to a single load device having a plurality of terminals individually requiring for normal operation different unidirectional operating potentials, the one of the terminals of highest potential comprising an anode electrode requiring a positive current thereto and the remainder of the terminals comprising secondary-cathode electrodes requiring negative currents the values of each of which are dependent upon the values of current to all of the terminals of lesser potential. Specifically, this single load device comprises an electron multiplier 12 having an output electrode or anode 13 requiring a positive current thereto, secondary cathodes 14-17, inclusive, which require negative currents thereto the values of each of which are dependent upon the values of current to all of the secondary cathodes of lesser potential, and a primary cathode 18. The common cathode K of rectifier 10 is connected to the anode or output electrode 13 of electron multiplier 12, which, under normal operating conditions, receives electrons, that is, requires a positive current, and has the most positive mean potential. The anodes A₁-A₄, inclusive, of rectifier 10 are respectively connected to the secondary cathodes 14-17, inclusive, of electron multiplier 12, which require negative electron currents and unidirectional operating voltages of progressively decreasing values, through windings S₁-S₄, inclusive. Anode A₅ is

connected to primary cathode 18, which also loses electrons, that is, requires a negative current, through winding S₅. That is, means are provided for connecting cathode K to anode 13, 5 which is the terminal of the single load device 12 of highest potential, and for connecting the anodes A₁-A₄, inclusive, of rectifier 10 of increasingly higher alternating potentials to the electrodes 14-18, inclusive, of electron multiplier 12, adapted for operation at decreasing unidirectional potentials, through their respective supply circuits S₁-S₅, inclusive.

Anodes A₁-A₄, inclusive, are perforated, so that some receive electrons that have passed 15 through the perforations of the others, and are spaced at increasing intervals from the cathode K. Under these conditions, it is desirable that they should not have high coefficients of secondary emission; for if they have, they might 20 lose rather than receive electrons.

It is apparent that, with the arrangement described, a single rectifier with a single cathode and a plurality of co-operating anodes is effective to supply unidirectional voltages of different 25 values to a plurality of terminals of a load circuit requiring different operating potentials without the use of voltage-divider resistors or other power-dissipative devices.

While there has been described what is at 30 present considered to be the preferred embodiment of this invention, it will be obvious to those skilled in the art that various changes and modifications may be made therein without departing from the invention, and it is, therefore, aimed 35 in the appended claims to cover all such changes and modifications as fall within the true spirit and scope of the invention.

What is claimed is:

1. In a power-translating system including a 40 single load device having a plurality of terminals individually requiring for normal operation different unidirectional operating potentials, the one of said terminals of highest potential requiring a positive current thereto and the remainder of said terminals requiring negative currents the value of each of which is dependent upon the values of current to all of said terminals of lesser potential, a power-supply system comprising, a rectifier including a cathode and a plurality of anodes, a plurality of supply circuits for supplying alternating potentials of different values between the several anodes and said cathode, and means for connecting said cathode to said one of said terminals and 45 for respectively connecting said anodes of increasingly higher alternating potential to said terminals adapted for operation at decreasing unidirectional potentials through their respective supply circuits.

2. In a power-translating system including a 55 single load device comprising an electron multiplier having primary-cathode and anode electrodes and at least one secondary-cathode electrode, said anode electrode requiring a positive current thereto and said secondary-cathode electrode requiring a negative current thereto dependent upon the value of the current to said primary-cathode electrode, a power-supply system comprising, a rectifier including a cathode and a plurality of anodes, a plurality of supply circuits for supplying alternating potentials of different values between the several anodes and said cathode, and means for connecting said cathode of said rectifier to said anode electrode 60 of said electron multiplier and for connecting

said secondary-cathode and said primary-cathode electrodes, respectively, to said anodes of increasingly higher alternating potential through their respective supply circuits.

3. In a power-translating system including a single load device comprising an electron multiplier having primary-cathode and anode electrodes and a plurality of secondary-cathode electrodes adapted for operation at different unidirectional potentials, said anode electrode requiring a positive current thereto and said secondary-cathode electrodes requiring negative currents thereto the value of each of which is dependent upon the values of current to all of said electrodes of lesser potential, comprising, a rectifier including a cathode and a plurality of anodes, a plurality of supply circuits for supplying alternating potentials of different values between the several anodes and said cathode, and means for connecting said cathode of said rectifier to said anode electrode of said electron multiplier and for connecting said secondary-cathode electrodes adapted for operation at decreasing unidirectional potentials and said primary-cathode electrode, respectively, to said anodes of increasingly higher alternating potential through their respective supply circuits.

4. In a power-translating system including a single load device having a plurality of terminals individually requiring for normal operation different unidirectional operating potentials, the one of said terminals of highest potential requiring a positive current thereto and the remainder of said terminals requiring negative currents the value of each of which is dependent upon the values of current to all of said

10 terminals of lesser potential, a power-supply system comprising, a rectifier including a cathode and a plurality of anodes, a plurality of supply circuits each including a different winding of a common transformer for supplying alternating potentials of different values between the several anodes and said cathode, and means for connecting said cathode to said one of said terminals and for respectively connecting said anodes of increasingly higher alternating potential to said terminals adapted for operation at decreasing unidirectional potentials through their respective supply circuits.

5. In a power-translating system including a single load device having a plurality of terminals individually requiring for normal operation different unidirectional operating potentials, the one of said terminals of highest potential requiring a positive current thereto and the remainder of said terminals requiring negative currents thereto for normal operation of said load device, a power supply system comprising, a rectifier including a cathode and a plurality of perforate anodes spaced at increasing intervals from said cathode, a plurality of supply circuits for supplying alternating potentials of different values between the several anodes and said cathode, and means for connecting said cathode to said one of said terminals and for connecting said anodes of increasingly higher alternating potential to said terminals adapted for operation at decreasing unidirectional potentials through their respective supply circuits.
